CLAIM

The ornamental design for a display housing, as shown and described.

DESCRIPTION

FIG. 1 is a left, front perspective view of a computer display showing our new design;

FIGS. 2 and 3 are respectively top and bottom plan views thereof;

FIGS. 4, 5 and 6 are respectively front, rear and right sides elevation views thereof;

FIG. 7 is a left, front perspective view of a second embodiment of our new design;

FIGS. 8 and 9 are respectively top and bottom plan views thereof;

FIGS. 10, 11 and 12 are respectively front, rear and right side elevation views thereof;

FIG. 13 is a left, front perspective view of the display housing shown in FIG. 7 with the tiltable cover being tilted to an alternate position;

FIGS. 14 and 15 are respectively top and bottom plan views thereof;

FIGS. 16, 17 and 18 are respectively front, rear and right side elevation views thereof; and

FIG. 19 is a right, rear perspective view thereof.
